CLAIM

The ornamental design for a multi-tool apparatus, as shown and described.

DESCRIPTION

FIG. 1 is a perspective view of my ornamental design for a multi-tool apparatus in a folded form;

FIG. 2 is a perspective view of the design of FIG. 1 in an unfolded form;

FIG. 3 is a right side elevation view of the design of FIG. 1; FIG. 4 is a left side elevation view of the design of FIG. 1; FIG. 5 is a front side edge view of the design of FIG. 1; FIG. 6 is a rear side edge view of the design of FIG. 1; FIG. 7 is a top plan view of the design of FIG. 1; and, FIG. 8 is a bottom plan view of the design of FIG. 1. The structure depicted by means of broken lines in FIG. 1 has been shown for illustrative purposes only and forms no part of the claimed design.
